UNITED STATES PATENT OFFICE.

WILLIAM J. DUDLEY AND THOMAS AUGUSTUS RICHARD, OF WILMINGTON, OHIO.

EGG-TURNING TRAY.

1,270,931.

Specification of Letters Patent.

Patented July 2, 1918.

Application filed March 11, 1918. Serial No. 221,764.

To all whom it may concern:

Be it known that we, WILLIAM J. DUDLEY and THOMAS A. RICHARD, citizens of the United States, residing at 155 Rombach 5 avenue, Wilmington, in the county of Clinton and State of Ohio, have invented certain new and useful Improvements in Egg-Turning Trays; and we do declare the following to be a full clear, and exact description of the invention, such as will enable others skilled in the art to which it appertains to make and use the same.

This invention relates to incubators, and relates more particularly to an improved 15 form of egg-turning device or tray.

One of the objects of this invention is to provide a thoroughly effective means of assuring the removal of the tray from the incubator, in order that the eggs must essentially be temporarily exposed to the cooling 20 effects of the air extraneous to the incubator casing as a prerequisite to the turning of the eggs.

Another object is to provide a device of 25 this character that may be operated from either of two opposite sides.

Another object is to minimize the cost of manufacture of incubators, by greatly simplifying the construction thereof.

Another object is to prevent excessive 30 turning of the eggs by unauthorized persons, or will permit a regular attendant to turn them as often as he deems necessary.

Other objects and advantages may become apparent to persons who read the following details of description in connection 35 with the accompanying drawings in which:

Figure 1 is a vertical sectional view through an incubator comprising the preferred embodiment of our invention.

Fig. 2 is a perspective view illustrating 40 one of our improved egg-turning trays in position upon one of the nurseries, said tray and nursery being detached or removed from the casing of the incubator;

Fig. 3 is a top plan view illustrating one 45 of the egg turning trays having one of our improved turning attachments applied thereto;

Fig. 4 is an enlarged fragmental sectional view showing the construction of our 50 improved turning attachments and its connections with one of the egg-turning rollers; and

Fig. 5 is a perspective view showing our 55 improved turning attachment detached.

Referring to these drawings in detail, in which similar reference characters correspond with similar parts throughout the several views, the incubator casing 10 may 60 be of any ordinary construction, which is provided with a door 10' or a cover 11 and supporting strips 12. Upon the strips 12 may be supported a nursery 13 of any appropriate construction, the bottom 14 of the nursery preferably being formed of wire netting or other reticulated material.

The improved tray comprises a four-sided open frame consisting of imperforate side members 15 and perforated side members 16, 70 the perforations or apertures 17 of which provide bearings for receiving the opposite ends 18 of the egg-turning rollers 19. The bearings 17 support the rollers 19 in such parallel and spaced relation to one another 75 that the eggs to be supported thereby cannot fall therebetween. The ends of the rollers 19 terminate substantially at the outer surfaces of the sides 16, so that such ends present no obstruction to the movement of the 80 tray in and out of the casing 10. As shown in Figs. 1, 2, and 3, the ends of the rollers are each provided with a non-cylindrical socket 20, these sockets being adapted to receive a non-cylindrical portion of the turning attachment which is described in detail herein-after. The rollers are preferably reduced 85 at their ends so as to provide shoulders 21 which prevent longitudinal movement of the rollers with relation to the sides 16. 90

As shown in Fig. 1, the walls of the casing 10 are imperforate, so as to prevent access to the sockets 20 when the tray is in the casing. This necessitates the removal of the tray from the casing, through door 10', 95 as a prerequisite to engaging the turning attachment with the sockets 20. By thus requiring the removal of the tray from the casing, the proper and necessary airing and cooling of the eggs is assured. In this connection it may be well to explain that experience has taught that in incubating eggs, it is necessary that they be allowed to cool somewhat, at regular intervals, so that the chicks are aroused from their dormant state, while the egg shells become more brittle, and the breaking of the shells becomes more nearly assured. In other words, the 100 105

percentage of chicks hatched from the eggs is greatly increased by such regular cooling. It has also been found by experience, that the cooling of the eggs in an incubator is 5 likely to be neglected if the turning of the eggs can be accomplished without removing the egg tray from the incubator. Moreover, it is sometimes true that persons other than the incubator attendants are admitted into 10 the presence of the incubator, and that such persons are likely to meddle with the turning devices when such are accessible. Such unauthorized turning of the eggs might be so excessive as to cause very serious detriment thereto, or it might be only sufficient to turn the eggs back to the position from which they had been recently turned, thereby off-setting the good effect obtained by the proper turning thereof.

15 Moreover, in contradistinction to some known incubators, which are provided with normally accessible turning devices whereby all the eggs in a tray may be simultaneously turned, this present form of egg turning 20 tray is comparatively inexpensive, whereas the devices referred to are essentially very expensive because of the provision of a turning device for each tray. In this present invention, it is necessary, as explained 25 before, to remove the tray for cooling the eggs, but it is not necessary to remove the tray to take chicks from the nursery. Only open incubator door and lift up front of tray and insert hand into nursery and take 30 out chicks.

The turning attachment, shown separately in Fig. 5, will now be described as follows:

This turning element consists of a plurality of crank members 22, a spacing member or bar 23, and a handle or handle bar 24. Each member 22 comprises a roller-engaging element 25, a handle-engaging element 26 and a crank element 27 between the elements 25 and 26. The roller engaging element is 40 provided with a shoulder 28 and a non-cylindrical end portion 29, the latter fitting snugly in the non-cylindrical apertures 20 of the rollers 19. The handle member 24 is secured on the elements 26 by means of 45 heads 30 formed on the latter, and these elements 26 are rotatable in the respective bearings formed through the handle bar 24. The spacing bar 23 is formed with apertures or 50 bearings 31 which are spaced commensurately with the spacing of the sockets 20, so that the non-cylindrical portions 29 of the cranks 22 are accurately guided to the sockets 20 when any one of said portions 29 is 55 in registry with the corresponding socket 20. It will be seen therefore, that the turning attachment may be very quickly applied for rotating all of the rollers 19 simultaneously, and that in thus applying the attachment all of the elements 29 are simultaneously 60 engaged with the sockets 20. More-

over, it will be seen that this attachment is transferable and interchangeable with relation to the trays, and may be carried by the incubator attendant from one to another tray and from one to another incubator so 70 that he may not only turn the eggs quickly and conveniently, but is compelled, as a prerequisite to the turning thereof, to subject the eggs to the cooling effects of the extraneous air.

Although we have described this embodiment of our invention in very minute detail it is not intended to limit the invention to these exact details of construction and arrangement of parts, but we are entitled to 80 make such minor changes that do not constitute a departure from the inventive ideas disclosed in the foregoing description and following claims.

We claim:

1. In an incubator, a hollow frame provided with a row of bearings at each of two opposite sides, a plurality of egg-supporting rollers journaled in said bearings and terminating substantially at the outer surfaces of said opposite sides, a casing normally inclosing said frame and preventing access to the ends of said rollers, and means engageable with the ends of said rollers for turning them and the eggs thereon when 95 said frame is removed from said casing, said means being disengaged from said rollers when said frame is within said casing, whereby it is essential that the eggs on said rollers be exposed to the air extraneous to 100 said casing when the rollers are turned by said means.

2. In an incubator, a hollow frame provided with a row of bearings at each of two opposite sides, a plurality of egg-supporting rollers journaled in said bearings and terminating substantially at the outer surfaces of said opposite sides, a casing normally inclosing said frame and preventing access to the ends of said rollers, and means engageable with the ends of all of said rollers simultaneously for turning them and the eggs thereon when said frame is removed from said casing, said means being disengaged from said rollers when said frame is 115 within said casing, whereby it is essential that the eggs on said rollers be exposed to the air extraneous to said casing when the rollers are turned by said means.

3. In an attachment for simultaneously 120 engaging a plurality of rollers so as to simultaneously turn the rollers, a plurality of crank members each comprising a roller-engaging element and a handle-engaging element and a crank element, a spacing member provided with a plurality of bearings in which said roller-engaging elements are journaled, and a handle common to all the said handle-engaging elements and operatively connected to the latter, said attach- 125 130

ment being bodily transferable from one set of rollers to a similar set of rollers.

4. In an attachment for simultaneously engaging a plurality of rollers so as to simultaneously turn the rollers, a plurality of crank members each comprising a roller-engaging element and a handle-engaging element and a crank element, a spacing member provided with a plurality of bearings in which said roller-engaging elements are journaled, and a handle common to all the said handle-engaging elements and operatively connected to the latter, said roller-engaging elements being provided with

means for retaining engagement of said 15 spacing member with said roller-engaging elements so that the attachment may be quickly and successively attached to a plurality of similar sets of rollers.

In testimony whereof we have hereunto 20 set our hands in the presence of two subscribing witnesses.

WILLIAM J. DUDLEY.
THOMAS AUGUSTUS RICHARD.
